UNITED STATES PATENT OFFICE.

JOHN SANFTLEBEN, OF QUINCY, ILLINOIS.

HARNESS-SADDLETREE.

SPECIFICATION forming part of Letters Patent No. 736,026, dated August 11, 1903.

Application filed November 1, 1902. Serial No. 129,748. (No model.)

To all whom it may concern:

Be it known that I, JOHN SANFTLEBEN, a citizen of the United States, residing at Quincy, in the county of Adams, State of Illinois, have 5 invented certain new and useful Improvements in Harness-Saddletrees; and I hereby declare the following to be a full, clear, and exact description of the same, reference being had to the accompanying drawings, forming a part of this specification, and to the letters of reference marked thereon.

This invention relates to improvements in harness-saddletrees designed especially for coach or team pads, formed of pressed steel, 15 aluminium, or other metal; and the invention consists in certain novel details of construction and combinations and arrangements of parts, all as will be now described, and the particular features of novelty pointed out in 20 the appended claims.

In the drawings, Figure 1 is a side elevation of a harness-saddle, showing my improved tree, one end in section. Fig. 2 is a view from the under side of the yoke and one 25 of the jockey-plates separated from each other. Fig. 3 is a detail view of the inlay or filling-piece for the yoke. Fig. 4 is a perspective view of a jockey-plate and yoke with coupling-piece, the parts being shown separated. Fig. 5 is a view from the under side, showing modified construction of jockey and yoke.

Similar letters of reference in the several figures indicate the same parts.

35 In the accompanying drawings the letter A indicates the pad, and B the skirt, these being of the usual or any preferred construction. C indicates the yoke, formed of pressed steel, aluminium, or other metal and provided with the downwardly-turned flanges c c. The yoke C and jockey D are preferably hinged or pivoted together, the hinge or pivot-joint being constructed as follows: At each end of the yoke and preferably centrally 40 thereof there is a small tongue or strip of metal, which is bent back to form loop a, and at the coöperating end of the jockey-plates D there are two tongues or strips of metal, preferably one at each side, which are bent back 45 to form loops d d. These loops d d preferably extend back on the jockey-plate a short distance and are relatively wide for a pur-

pose to be presently explained. A pin E is held in the loops d d of the jockey-plate, and the loop a of the yoke is bent around the pin, 55 thus connecting the jockey and yoke and permitting a pivotal action between the two, as will be readily understood.

The jockey-plates, like the yoke, are provided with depending side flanges d' and also, 60 like the yoke, are formed of pressed steel, aluminium, or other metal. The jockey-plates are held in place on the pad by the terrets F and screws G, and when the terrets are screwed down in place the pad will be 65 prevented from being drawn in by the comparatively wide flat faces of the loops d d, resting on the pad.

Struck up from the metal of the jockey-plates are two triangular spuds or prongs H, 70 the points of which penetrate the skirt B and serve to hold the same in place. It will be noted that these spuds H and the screw G make three points of contact with the skirt, effectually preventing sidewise motion of the 75 skirt, and thereby insuring its being held securely in place, as will be readily understood.

To strengthen the yoke C, I preferably employ an inlay or filling-piece I of metal formed with the upturned side flanges i and with a 80 central longitudinal slot or opening i², having the marginal upturned flanges i³. The yoke is held in place on the pad by means of the check-hook K and screws J, which pass through suitable holes in the yoke and through 85 the slot i in the filling-piece, being screwed into the pad. This filling-piece prevents the pad from being drawn in by the hook and screws when screwed home. Instead of connecting the yoke and jockeys directly together I may employ a coupling, as illustrated in Fig. 4. In this construction the yoke C' is provided at the ends with a transverse slot c', with which engages the hooked end c² of the coupler M. This coupler is held 90 in place by the terrets, as will be readily understood. In connection with this form of coupling I have illustrated a modified construction of yoke and jockey-plates. As in the other construction, these yokes and plates 95 are formed of pressed metal. The opening a² for the passage of the check-hook shank is made square and the metal turned down to form projections a³, against which the nut 100

in the pad into which the check-hook screws will bear and prevent the pad from being drawn in by the terret. The jockey-plate D' is also provided with a square opening d^3 , through which the terrets pass, the metal of the plate being turned down to form projections d^4 , which, like those on the yoke, prevent the pad being drawn in when the terrets are screwed home, as will be understood.

10 Having thus described my invention, what I claim as new, and desire to secure by Letters Patent, is—

1. In a harness-saddletree, the combination with the pad and skirt, of the yoke, the jockey-
15 plates, the spuds in said plates, the screw for securing the plate to the pad, said screw and

spuds being triangularly disposed whereby the skirt will be held from lateral distortion; substantially as described.

2. In a harness-saddletree, the combination 20 with the pad and skirt, of the yoke, the jockey-plates pivotally connected thereto, said plates and yoke formed with depending side flanges, and the filling-piece for the yoke having the upturned side flanges, and longitudinal slot 25 or opening, provided with marginal upturned flanges, substantially as described.

JOHN SANFTLEBEN.
